UNITED STATES PATENT OFFICE.

ANDREW L. TIFFANY, OF FULLERTON, CALIFORNIA.

BROOM-HOLDER.

1,162,891.

Specification of Letters Patent.

Patented Dec. 7, 1915.

Application filed June 23, 1915. Serial No. 35,870.

To all whom it may concern:

Be it known that I, ANDREW L. TIFFANY, a citizen of the United States, residing at Fullerton, in the county of Orange and 5 State of California, have invented certain new and useful Improvements in Broom-Holders, of which the following is a specification, reference being had to the accompanying drawings.

10 My present invention relates to new and useful improvements in broom holders and has particular reference to devices of this character which are adapted to yieldably grip the handle of the broom.

15 One of the principal objects of the invention is to provide a broom holder of the character specified, which consists merely in a wall plate or block and a gripping device which is attached thereto and is formed 20 from a single length of wire bent to form a pair of resilient gripping jaws.

The above, and other incidental objects of a similar nature, which will be hereinafter 25 more specifically treated are accomplished by such means as are illustrated in the accompanying drawings, described in the following specification, and then more particularly pointed out in the claim which is appended hereto and forms part of this application.

With reference to the drawings, wherein there has been illustrated the preferred embodiment of this invention, as it is reduced to practice, and throughout the several views 35 of which similar reference numerals designate corresponding parts, Figure 1 is a view in elevation showing the device applied to the wall of a room and supporting a broom; Fig. 2 is a view in top plan, showing the broom gripped in the jaws of the device, the wall block being fragmentarily shown in section; Fig. 3 is a detail view illustrating the manner in which the wire from which the gripping device is made, is first bent; 40 Fig. 4 is a detail view showing the next step in the bending of the wire; and Fig. 5 is a detail view showing the following step in the bending of the wire.

As is best disclosed in Fig. 1, the broom holder consists in a wall plate or block A, and a gripping device, generally designated by the numeral B. The wall block or plate is preferably formed from a small piece of wood, although it may be made, if desired,

from rubberoid or any other suitable composition or metal, without departing in any way from the spirit of the present invention.

The gripping device generally designated by the letter B is, as previously designated, formed from a single length of resilient wire 60 of medium gage. The wire is initially bent at its approximate center to define, as in Fig. 3, a single convolution helix 10 and is then bent as in Fig. 4 to produce oppositely curved arms 11. After the two portions of 65 the wire have been bent to form these arms, they are extended horizontally for a short distance, as indicated at 12 and are then bent, as in Fig. 4, to produce two additional single convolution helixes, as indicated at 70 13 and 14. After the formation of the members 13 and 14, the two portions of the wire are directed toward each other and at a slight downward angle, forming the cross arms 15 and 16, as in Fig. 5. As shown in 75 Fig. 2 the terminals of these arms 15 and 16 are bent toward each other and away from the members 13 and 14, producing the loops 17 and 18. The extreme terminals of the wire are bent, as at 19 and 20 to produce 80 the diverging stubs 21 and 22. It is now to be observed that the curved portions 19 and 20 at the ends of the loops 17 and 18 are normally disposed in proximity to each other and that the distance between these 85 portions 19 and 20 and the arms 15 and 16 is less than the diameter of an ordinary broom handle. Thus, when as in Fig. 2 the broom handle is passed between the members 21 and 22 and spreads the portions 19 and 90 20, it will engage with the arm 15 (which bears against the outside of the arm 16) without allowing the portions 19 and 20 to come back to their normal position. Thus, when the broom is inserted in the loops 17 95 and 18, the portions 19 and 20 constitute yieldable gripping jaws which serve to support the broom handle and yieldably maintain it against displacement from the holder.

In attaching the gripping plate to the block plate A, I preferably employ three staples 23, 24 and 25 which are respectively applied to the member 10 and the curved portions 11 and 12. By applying the three 105 staples at these points, the gripping device is securely attached to the block and is held against turning thereon.

Attention is now directed to the fact that the gripping device is so formed that the convolutions 13 and 14 as well as the arms 15 and 16 serve to grippingly engage the jaws 19 and 20 with the broom. Also the loops 17 and 18 contribute to the gripping of the broom handle, since the broom, when inserted in the member shown in Fig. 2, serves to space the jaw members 19 and 20, away from the members 15 and 16, a distance greater than the normal space between these members. Such spacing of the jaws 19 and 20, from the members 15 and 16, is accomplished in opposition to the tension of the loops 17 and 18 and these members, therefore, obviously, serve to increase the gripping action of the jaws.

In reduction to practice, it has been found that the form of this invention illustrated in the drawings and referred to in the above description as the preferred embodiment, is the most efficient and practical; yet realizing that the conditions concurrent with the adoption of this device will necessarily vary, it is desirable to emphasize the fact that various minor changes in the details of construction, proportion and arrangement of parts may be resorted to, when required, without sacrificing any of the advantages of

this invention, as defined by the appended claim.

What is claimed is:—

A broom holder formed from a single length of wire bent to form a pair of transversely spaced helixes, arms extending from the helixes, said arms being downwardly directed and being crossed, loops formed from the terminals of the arms and positioned at opposite sides of the overlapping point of the arms, the terminals of the arms being bent toward each other and away from the arms and at substantially right angles to the helixes to form gripping jaws, said jaws being normally disposed in proximity to each other and being spaced from the arms a distance less than the diameter of the broom handle to be held, whereby the jaws tend, when a broom is inserted in the gripping device, to engage against the handle at spaced points and to move toward each other and to also move toward the arms, thereby forcing the handle against said arms.

In testimony whereof I hereunto affix my signature in the presence of two witnesses.

ANDREW L. TIFFANY.
